COMBINATION WATER FEEDER AND OVER-FLOW DEVICE

Frank H. Mayer, Weehawken, N. J., assignor to
Kieley & Mueller Inc., New York, N. Y.

Application March 1, 1932, Serial No. 596,115

6 Claims. (Cl. 137—101)

My invention relates to a combination water feeder and overflow device and has for its particular object the provision of a combination device of this character for heating systems and the like and particularly those known as vacuum or suction systems.

My invention is of broad application and is applicable for use with many types of water systems, but has been shown herein for illustrative purposes only in connection with a simple heating system such as is commonly used for dwellings and the like and wherein a boiler is provided for generation of steam for passage to the various heating units.

An important object of my invention lies in the provision of means for automatically maintaining a constant water level in the boiler of the unit both by controlling the water supply to fill the boiler to a predetermined level and by controlling automatically a discharge passage whereby to lower the level of the water in case it gets too high.

A further object of my invention is to provide a mechanism for such control, which is operative and effective under conditions of vacuum used in many heating systems.

Another object of my invention lies in the provision of a novel overflow device provided with valve operating means operable under either conditions of vacuum or pressure.

Other objects and advantages in details of construction will be apparent as the description proceeds, reference now being had to the figures of the accompanying drawing forming a part of this application and wherein like reference numerals indicate like parts.

In the drawing:

Figure 1 is a cross sectional view of my improved combination water feeder and overflow device.

Figure 2 is a somewhat diagrammatical view illustrating the relation of my invention to a typical boiler.

Figure 3 is a detail sectional view showing the arrangement of the passageways 41 and 42 in the valve casing in the overflow device.

Referring generally to Figure 2, the reference character 1 indicates a boiler of any conventional design or construction and which has not been illustrated in detail as it forms no part of this invention. Suffice it to say that the boiler is supplied with the usual water chamber and heating device therefor by means of which steam may be generated therein for passage outwardly to

the various heating elements such as radiators and the like.

The pipe 2 may constitute the main source of water supply for the boiler 1, communicating with such boiler through the pipes 3, 4, 5, 6, and 7, and automatically controlled at the point where it communicates with the water feeder by mechanism within the water feeder casing 8, the details of which will be presently described. The passage 9 is the ordinary by-pass usually provided in such systems.

The pipe 10 connects the boiler 1 and the water feeding casing 8 and acts as a water level equalizer between these units, the level of the water in the boiler and in the water feeding casing being registered by the gauge 11. The pipe 12 connects the upper ends of the boiler 1 and the water feeder 8 and serves as a steam equalizer and is also common construction and practice.

Referring now particularly to Figure 1 of the drawing, it will be noted that within the water feeder casing 8 there is provided a float 13 adapted to raise and lower within the casing with the level of the water therein. This float 13 is pivotally connected at its lower end by means of the link 14 to one end of a link 15, pivoted intermediate its ends as at 16 to one arm of a bracket 17. The opposite end of the link 15 is pivotally connected to a link 18 also pivotally connected at its opposite end with a link 19 substantially parallel with the link 15, which link 19 is pivoted at its opposite end as at 20 to another arm 21 of the bracket 17. Suitably secured as at 22 to the link 19 is one end of a vertically disposed valve stem 23, the lower end of which is provided with a valve 24 cooperating with a valve seat and passage 25 which communicates on one side with the water supply pipes 4, 3, and 2 and on the opposite side with the pipes 5, 6 and 7. The bottom 26 of the water feeder 8 is preferably secured in position by means of the bolts 27 and is provided with the depending casting or valve housing 28 within which the valve 24 is disposed and through which the passageways communicating with the valve seat and passage 25 are provided. The passageways into and out of this valve casing are threaded as at 29 to receive the ends of the pipes 4 and 5. The valve stem 23 is supported and guided in its vertical movement by means of an elongated bearing 30 suitably threaded as at 31 through an opening in the bottom member 26. As shown clearly in Figure 1, the bracket 17 is supported upon this bearing 30.

In operation it will be obvious that if the water level in the water feeder casing 8, and consequent- 55

ly in the boiler 1, falls below the predetermined or desired level, the float 13 will be lowered and this movement through the links 14, 15, 18 and 19 causes the valve stem 23 to be raised, thus opening the valve 24 and permitting the water to pass through the valve casing 28 into the boiler, the level of which equalizes in the water feeder casing 8 by means of the pipe 10. Obviously when the predetermined level of the water has again been reached the float in raising to such level, again through the links 14, to 19 inclusive, causes the valve stem and valve 24 to again be lowered against the valve seat 25 and thus stops the further passage of water into the boiler.

15 One side of the water feeding casing 8 is provided with the threaded outlets or passageways 32 to receive the fittings for the level gauge 11. The upper end of the casing 8 is also provided with a threaded outlet 33 to receive the fitting for the pipe 12.

20 The water feeder casing 8 is provided on the side opposite the water gauge 11, with a spaced flanged extension portion 34 secured to which, as by the flange 35 and bolts 36, is the overflow device casing 37.

25 On the interior of the overflow casing 37 and secured to the flanged portion 34, independently of the casing 37, as by the bolts 38, is a supporting member 39 provided adjacent its top with a preferably cast integral casing 40 provided with independent cores or passageways 41 and 42 suitably separated as by means of the partition 43. The passageway 41 communicates with a similar passageway 44 formed in the extension 34, the latter passageway communicating with the atmosphere through a vent 45 on such extension. The passageway 42 communicates with a passageway 46 opening directly into the casing 8. As shown in Figure 1 the air passageway 44 does not communicate with the interior of the casing 8 but is suitably formed in the shell of such casing. It will also be noted with reference to Figure 1 that the side wall of the casing 8 adjacent the overflow casing 37, is spaced from the flanged portion 34, such flanged portion constituting in effect an extension on the outer shell of the casing 8.

30 The lower end of the supporting member 39 within the overflow casing 37 is also provided with a preferably cast integral casing 47 provided with a passageway 48 communicating at one end through the flanged extension 34 with an outlet passage 49 to which is connected the discharge pipe 50 (see Figure 2).

35 Secured within the overflow casing 37, to the supporting member 39 and between the housings 40 and 47, as by the bolts 51, is a bracket 52. Pivoted on this bracket 52 as at 53, is a bell crank 54, one end of which is provided with oppositely inclined surfaces 55 and 56 joining in an apex 57. The opposite end of the bell crank 54 is provided with the slot 58 within which engages a pin 59 carried by a vertically disposed valve stem 60, the upper end of which is provided with a valve 61, cooperating with a suitable valve seat and opening in the housing 40 and communicating with the air passageway 41. The lower end of the valve stem 60 is also provided with a valve 62 cooperating with a suitable valve seat and opening in the housing 47 and communicating with the discharge passageway 48. These valves are so arranged that when the valve stem 60 is in its uppermost position, the air passageway 41 is closed to the interior of the overflow casing 37 and the discharge passageway 48 is likewise closed from the interior of the overflow casing. When,

however, the valve stem 60 is lowered, the air passageway and the water discharge passageway are both opened to communicate with the interior of the overflow housing 37.

5 Adjacent the upper end of the valve stem 60 and below the valve 61 thereon, there is pivoted to the valve stem, as at 63, one end of a link 64 pivoted intermediate its ends as at 65 to a supporting lug 66 carried upon the casing 40. The opposite end of the link 64 is pivoted to a valve stem 67 carrying a valve 68 adapted to cooperate with a valve seat and opening in the casing 40 and communicating with the water passage 42 thereof. It will be clear that when the valve stem 60 is raised as shown in Figure 1, the valve 68 is opened so as to admit water flowing from the water feeding casing 8 through the passages 46 and 42 into the overflow casing 37. When the valve stem 60 is lowered, the valve 68 will close such passage and prevent the flow of water into the overflow casing 37.

10 Pivot to the bracket 52 as at 69 is an elongated arm 70 secured to the opposite end of which is the float 71 within the overflow casing 37. The end of this arm 70, adjacent its pivot point 69, carries an upwardly extended lug 72 having a pivotal connection as at 73 with one end of a link 74, the opposite end of which carries a roller 75 engageable with one or the other of the inclined surfaces 55 and 56 on the bell crank 54.

15 Suitably connected to the link 74 and substantially centrally thereof, is a downwardly extending link 76, the lower end of which has secured thereto, one end of a coil spring 77, the opposite end of which is anchored as at 78 to an anchor pin 79 rigidly secured in the casing 47. These ends normally exert a strong downward pull upon the link 74 and consequently upon the inclined surfaced end of the bell crank 54. The inclined surfaces 55 and 56 of this bell crank are so disposed with respect to the pivot point 53 thereof, that when the roller 75 of the link 74, engages the inclined surface 55, the bell crank is rocked on its pivot 53, thus raising the opposite end thereof and simultaneously raising the valve stem 60 whereby to close the valves 61 and 62, and open the valve 68. This is the normal position of these parts.

20 If, however, the water level in the boiler 1 and consequently in the water feeding casing 8, should rise above its predetermined point, due perhaps to the return to the boiler of condensed steam in the heating system through the return pipe 1a and thus overflow through the passages 46 and 42 and through the valves 68, into the overflow casing 37, the float 71 therein will rise, carrying with it the arm 70 and thus tending to rock the lug 72 on such arm to the right in Figure 1. This movement exerts a pull to the right on the link 74 and causes the roller 75 to ride up over the inclined surface 55 and over the apex 57 on to the inclined surface 56 of such bell crank, in which position the spring 77, exerting its downward pull or tension, causes such roller to rock the bell crank 54 on its pivot to the left in Figure 1, and thus causing the valve stem 60 to be moved downwardly, resulting in opening the valve 61 to the atmosphere passage and opening the valve 62 to the discharge passage and simultaneously closing the valve 68 and preventing the flow of any more water into the overflow casing.

25 It will be understood that when this device is connected with a heating system using suction or a partial vacuum as the circulating force, such suction or partial vacuum exists in the casings 8 and 37. Consequently with the opening of the

valve 61, to the air passage and admitting atmospheric pressure into the casing 37, the accumulated water therein is permitted to run out through the discharge passages 48 and 49. When the casing 37 has thus been emptied the float 71 naturally resumes its lowermost position as shown in Figure 1 and in moving back to such position, again rocks the arm 70 and the lug 72 which again forces the link 74 to the left in Figure 1, causing its roller 75 to ride up over the inclined surface 56 and past the apex thereof, whereupon the spring 77 snaps the bell crank 53 again to the right in Figure 1, thus raising the valve stem 60 and closing the valve 61 to the air passage and the valve 62 to the discharge passage, and opens the valve 68 to the water overflow passages 42 and 46.

In this way the overflow of water, caused by an excess return of condensed steam, is taken care of and discharged. These parts all act automatically and require no attention beyond an occasional cleaning and adjustment.

It will be obvious from the foregoing description that the same parts herein described function equally well when used with a heating system which utilizes pressure instead of vacuum as the circulating agency. The spring controlled valve action provided herein, however, renders the device particularly adaptable for vacuum systems.

Of course, changes may be made in details of construction and arrangement of parts without departing from the spirit and scope of my invention. I do not limit myself, therefore, to the exact form herein shown and described other than by the appended claims.

I claim:

1. In combination with a boiler, an automatic water feeder operatively connected therewith, a casing for said feeder provided with an extension, an overflow control device communicating with said feeder and secured to said extension, a discharge passage formed in said device and said extension, a valve controlling said passage, and float controlled means for forcibly operating said valve.

2. In combination with a boiler, an automatic water feeder operatively connected therewith, a casing for said feeder provided with an extension, an overflow control device communicating with said feeder through said extension, a discharge passage and an air passage communicating with said device through said extension, valves controlling said passages, and float controlled means for forcibly operating said valves.

3. In combination with a boiler, an automatic

water feeder operatively connected therewith, a casing for said feeder provided with an extension, an overflow control device communicating with said feeder through said extension, a discharge passage and an air passage communicating with said device through said extension, valves controlling said passages, and float controlled means for forcibly operating said valves, said valves and operating means being so arranged that said valves open and close together.

4. In combination with a boiler, an automatic water feeder operatively connected therewith, a casing for said feeder provided with an extension, an overflow control device communicating with said feeder through said extension, a discharge passage and an air passage communicating with said device through said extension, valves controlling said passages, float controlled means for forcibly operating said valves, said valves and operating means being so arranged that said valves open and close together, and a third valve adapted to open and close the communication between said device and said feeder and being so disposed as to open when the other valves are closed and vice versa.

5. In combination with a boiler, an automatic water feeder operatively connected therewith, a casing for said feeder provided with an extension, an overflow control device communicating with said feeder through said extension, a discharge passage and an air passage communicating with said device through said extension, valves controlling said passages, float controlled means for forcibly operating said valves, said valves and operating means being so arranged that said valves open and close together, and a third valve adapted to open and close the communication between said device and said feeder and being so disposed as to open when the other valves are closed and vice versa, all of said valves being actuated simultaneously and by the same operating means.

6. In combination with a water feeder, a feeder casing having an extension, an overflow device having a casing connected to said extension, an overflow passage through said extension communicating with both said casings, a discharge passage from said overflow device casing through said extension, valves controlling said passages, and float controlled means in said overflow device casing for forcibly actuating said valves to open said first passage and close the second and vice versa.

FRANK H. MAYER. 55
